US0D1040828S

(12) **United States Design Patent** (10) **Patent No.:** **US D1,040,828 S**
(45) **Date of Patent:** **** Sep. 3, 2024**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Freddy Anzures**, San Francisco, CA (US); **Stephen O. Lemay**, Palo Alto, CA (US); **Hoan K. Pham**, San Jose, CA (US); **Wan Si Wan**, Sunnyvale, CA (US)

(73) Assignee: **Apple Inc.**, Cupertino, CA (US)

(**) Term: **15 Years**

(21) Appl. No.: **29/871,146**

(22) Filed: **Feb. 13, 2023**

Related U.S. Application Data

(63) Continuation of application No. 29/769,332, filed on Feb. 4, 2021, now Pat. No. Des. 978,163, which is a continuation of application No. 29/619,679, filed on Sep. 29, 2017, now Pat. No. Des. 910,046.
